UNITED STATES PATENT OFFICE.

RONALD F. McFEELY, OF BEVERLY, MASSACHUSETTS, ASSIGNOR TO UNITED SHOE MACHINERY COMPANY, OF PATERSON, NEW JERSEY, A CORPORATION OF NEW JERSEY.

TOE-CUTTING ATTACHMENT FOR UPPER-STRETCHING MACHINES.

1,149,202.

Specification of Letters Patent.

Patented Aug. 10, 1915.

Application filed November 17, 1913. Serial No. 801,501.

To all whom it may concern:

Be it known that I, RONALD F. McFEELY, a citizen of the United States, residing at Beverly, in the county of Essex and State of Massachusetts, have invented certain Improvements in Toe-Cutting Attachments for Upper-Stretching Machines, of which the following description, in connection with the accompanying drawings, is a specification, like reference characters on the drawings indicating like parts in the several figures.

This invention relates to machines for stretching an upper over a last, such for example as pulling-over machines and lasting machines. Such stretching is usually preparatory to drawing the upper over the shoe bottom and fastening it to the innersole. One of the problems in securing satisfactory lasting is to dispose smoothly of the fullness of upper marginal material upon the shoe bottom about the toe. Thin and pliable materials are satisfactorily plaited and folded but stiff upper leather and bulky materials are lasted more smoothly in the manufacture of McKay shoes if they are slit and particularly if they are slit at each lateral side of the middle of the toe so that the fullness at opposite sides of the toe can be lapped over the stock at the end of the toe. This slitting can be performed advantageously in the pulling-over machine and automatic cutters have been proposed which were associated with the toe gripper. A difficulty heretofore experienced, however, has been that the slits formed in the up-drawn upper held by the gripper were not made to terminate at a uniform distance from the plane of the shoe bottom, but were dependent upon the position occupied by the gripper, which, in turn, varied with the elasticity of the upper being stretched. If a slit extends too close to the edge of the shoe bottom it shows in the finished shoe, producing damaged work. If it terminates too far from the edge of the shoe the upper cannot be lapped without forming a pucker.

The object of this invention is to overcome this difficulty and an important feature of the invention consists in the novel combination with a gripper and a cutter to slit the upper, of means to position the shoe, and operating mechanism for the cutter organized to form slits in the stretched upper that

will terminate at a uniform distance from the edge of the shoe bottom. Most conveniently the cutter moves with the gripper and it may advantageously be carried by the gripper. As herein shown there is employed the type of chisel-like cutters shown in prior United States Letters Patent No. 786,047, granted on my application Mar. 28, 1905, one cutter being mounted on each lateral edge of the gripper to cut downwardly along the edge of the gripper through the upper materials held taut by the gripper. In the machine of that patent there is nothing to predetermine with certainty the plane of the shoe bottom or the altitude of the portion of the shoe edge toward which the slitting knife is actuated. There is a rest engaging the shoe bottom at a single point and in practice the operator, who holds and positions the shoe entirely by his hands, fulcrums the shoe about the resting point and rocks the edge up or down according as the upper is short or long or is shorter on one side of the toe than on the other side. Therefore, in the practical use of that machine there is lack of uniformity in the relation of the terminal end of the slits to the shoe edge which this invention eliminates by the introduction into the combination of means to predetermine the plane of the shoe bottom and the altitude of the shoe edge relatively to the cutter actuating mechanism.

A further feature of this invention consists in the combination with a gripper, of guides on each lateral edge of the gripper, knives having their shanks mounted in the guides and means organized to operate the knives to form slits on opposite sides of the gripper. As shown in the drawings, the knives are operated to form simultaneously slits which converge toward the lower end of the gripper and the cutting stroke of the knives is terminated in a predetermined relation to the plane of the shoe engaging face of a sole rest which has a plurality of feet spaced apart longitudinally and transversely of the shoe so that the plane of the shoe bottom is established and the slits extend to a predetermined distance from the shoe edge.

The foregoing and other features of this invention, including certain details of construction and combinations of parts, will now be described with the aid of the accom-

panying drawings and the invention will then be particularly pointed out in the claims.

Figure 1 is a side elevation of so much of a pulling-over machine of the type disclosed in United States Letters Patent No. 1,029,387, granted on my application June 11, 1912, as is necessary for showing the present invention. Fig. 2 is a front elevation of the toe gripper and the actuating mechanism for the slitting knives. Fig. 3 is a perspective view of one of the slitting knives; and Fig. 4 shows a portion of a shoe, illustrating the operation of a machine equipped with the present invention.

The machine, as more fully explained in said last-mentioned patent, comprises a sole rest having a plurality of feet 2, 3, 4, engaging the shoe bottom at points spaced apart a substantial distance both widthwise and transversely of the shoe as shown in Fig. 4, and constituting a three-point bearing for determining the plane of the shoe bottom. While the sole rest is connected to operating mechanism and has certain movements fully described in said patent, those movements are uniform for each shoe and serve to position every shoe with its bottom in a predetermined plane at the conclusion of the upper stretching operation by the grippers. The machine comprises three or more grippers arranged at the opposite sides of the ball and at the end of the toe of which toe gripper 5 is shown in Figs. 1 and 2. The toe gripper is operated by power transmitted through yielding mechanism to stretch the upper and to come to rest holding the upper updrawn in a direction substantially perpendicular to the plane of the shoe bottom.

On each lateral edge of the toe gripper are formed guides 6 inclined downwardly toward each other. In the guides are fitted the preferably cylindrical shanks 8 bearing chisel-like knives 10, each knife being normally upheld by springs 12 inclosed within the shanks 8 and acting downwardly against a stud 14 projecting from the frame of the gripper into a slot 15 in the knife shank. The slot 15 is formed at its upper portion as a spiral so that during the latter part of the cutting stroke of the knife the knife is turned for producing a skiving form of cut at the termination of the slit 55 in the upper, the spiral in one shank being reversely inclined to that in the other to produce oppositely inclined bevels at the two sides of the gripper. The portion 16 of the machine frame within which the toe gripper is confined against lateral movement and guided in its updrawing movement and also in its overdrawing movement forms pivotal supports for rock-shafts 20 one at each side of the machine, as is shown in Fig. 2. Each rock-shaft has a depending

arm which is connected by a link 22 with the usual side clamp supporting arm 23 of the pulling-over machine which, in the normal operation of the machine, is moved inwardly toward the shoe to afford support for the shoe against the thrust of the drivers 24 which fasten the upper to the innersole by means of tacks, see Fig. 4. Each rock-shaft 20 has also an arm projecting inwardly toward the toe gripper and formed to engage under a shoulder of a spring pin 25 which constitutes the outer end of a lever 26 that is also fulcrumed upon the machine frame as clearly shown in Fig. 2. The inner end of each lever 26 rests upon the upper end of the adjacent knife shank 8, the end of the lever being broadened to cover the knife shanks in any of the positions to which the gripper is moved in over-drawing the upper. This arrangement provides that movement shall be transmitted from the power-operated side clamp arms 23 to lift the outer ends of the levers 26 and thereby depress the inner ends of those levers and thrust downwardly the knives 8 for slitting the upper while it is held taut by the toe gripper, a slit being formed at each side of the middle of the toe as indicated in Fig. 4. For adjustably predetermining the altitude to which the slitting knives shall be moved downwardly and thereby predetermining the relation of the terminal end of the slits so formed to the edge of the shoe bottom the spring-pressed pins 25 each have a laterally projecting stud 30 engaging a cam or wedge-shaped abutment 32 made adjustable in the machine frame by a slot and screw 33. The abutment serves to withdraw the pin 25 from operative engagement with the horizontal arm of the rock-shaft at times predetermined by its adjustment, such withdrawal predetermining the lower limit of movement imparted through the rock-shaft arm to lever 26 and to the knife. The relation of the terminal end of the slit to the shoe bottom is therefore made entirely independent of the position of the gripper and the length of its updrawing movement which, of course, varies with the elasticity of the stock and the location of said lower end of the slit is made to depend wholly upon the adjustment of the abutment 32 which, as well as the rock-shaft 20, is carried by the frame of the machine.

In the use of the machine the shoe is positioned with its bottom or innersole against the sole rest 2, 3, 4 and the upper is positioned within the jaws of the grippers after which the grippers are actuated for stretching the upper, the sole rest resisting displacement of the last and determining the plane of the shoe bottom with relation to the frame of the machine. The machine comes to rest at the end of the upper stretch-

ing operation to permit inspection and adjustment of the upper and last relatively. The machine is then re-started and the side clamp carrying arms moved toward position 5 for sustaining the shoe for the tacking operation. The first part of this movement of the side clamping arms is utilized for operating the toe slitting knives, the knives being thrust downwardly from the position 10 shown in Fig. 2 to slit the upper held under tension by the toe grippers. While the levers 26 are being moved for this purpose the abutments 32 force the pins 25 away from the rock-shaft arms and disengage the levers 15 from said arms thereby discontinuing the downward movement of the knives and locating the terminal ends of the slits relatively to the edge of the shoe bottom at points predetermined by the adjustment of 20 the abutments inasmuch as the plane of the shoe bottom has previously been predetermined by the sole rest. It is to be noted that at the time the knives are operated the shoe is fixed in its position entirely by the machine 25 and there is no opportunity for that position to be varied in a way to cause the slits to be terminated too remote from, or to be extended too close to, the edge of the shoe bottom. At the end of the machine's operation 30 the side clamp arms are moved outwardly thereby lowering the horizontal arms of the rock-shaft 20 and causing those arms to re-engage under the shoulders of the spring pins 25.

35 Having explained the nature of this invention and described a preferred construction embodying the same, I claim as new and desire to secure by Letters Patent of the United States:—

40 1. A machine for stretching shoe uppers having, in combination, means for predetermining the plane of the shoe bottom, a gripper, a knife, and automatic means for imparting to the knife an upper slitting movement extending through the upper held by the gripper and terminating at a predetermined distance from the plane in which the shoe bottom is maintained.

45 2. A machine for stretching shoe uppers having, in combination, a sole rest, a gripper, a knife, and means for imparting to the knife a slitting stroke extending into predetermined relation to the plane of the shoe engaging face of the sole rest, said sole rest 50 having a plurality of feet engaging the shoe bottom at points spaced apart transversely and longitudinally of the shoe whereby the plane of the shoe bottom is established and the relation of the terminal end of the slit 55 to the edge of the shoe bottom is established.

60 3. A machine for stretching shoe uppers having, in combination, a gripper, guides formed on each lateral edge of the gripper, knives having their shanks mounted in said 65 guides and means organized to operate both

knives simultaneously to form slits on opposite sides of the gripper.

4. A machine for stretching shoe uppers having, in combination, a gripper, guides inclined downwardly and inwardly toward 70 one another, knives having their shanks mounted in said guides, and means organized to operate both knives simultaneously to form converging slits on opposite sides of the gripper. 75

5. A pulling-over machine having, in combination, a sole rest, a gripper, a knife arranged to slit the upper pulled by the gripper, a side clamp carrying arm movable into and out of position for supporting a shoe 80 against the sole rest, and operating connections from said arm to the knife for causing the knife to do its work.

6. A pulling-over machine having, in combination, a sole rest, a gripper, a knife arranged to slit the upper pulled by the gripper, a side clamp carrying arm movable through varying distances into position to support shoes of different sizes against the sole rest, and operating connections from 85 said arm to the knife to impart to the knife a slitting movement terminating in predetermined relation to the plane of the sole rest. 90

7. A pulling-over machine having, in combination, a sole rest, a gripper, a knife arranged to slit the upper pulled by the gripper, a side clamp carrying arm movable into and out of position for supporting a shoe 95 against the sole rest, and operating connections from the arm to the knife organized for adjustment to cause the knife to cease to be actuated at a predetermined point in the movement of the arm which point can be adjusted. 100

8. A machine for stretching uppers having, in combination, a gripper, a frame relatively to which the gripper is movable for stretching the upper, a rest to engage the shoe bottom and resist the pull of the gripper, said rest having a bearing on the shoe bottom at a plurality of points spaced apart suitably to predetermine the plane of the shoe bottom, a slitting knife, a rock-shaft supported by the frame, operating connections from 110 the rock-shaft to the knife for moving the latter which connections can be adjusted to terminate the slitting movement of the knife at different points in the movement of the rock-shaft, and means for operating the 115 rock-shaft. 120

9. A pulling-over machine having, in combination, a gripper, a sole rest, a side clamp carrying arm which is movable into shoe supporting position, a slitting knife carried 125 by the gripper, a frame relatively to which the sole rest has predetermined positions, a rock-shaft supported by the frame, and operating connections from the side clamp carrying arm through the rock-shaft to the 130

knife for effecting a slitting stroke of the latter into predetermined relation to the sole rest.

10. A machine for stretching shoe uppers having, in combination, a gripper, guides formed on each lateral edge of the gripper, knives having their shanks mounted in said guides, and means organized to advance both knives simultaneously and to turn the two knives in opposite directions for forming slits on opposite sides of the gripper to pro-

duce a tongue of leather held by the gripper and having its opposite edges reversely skived.

In testimony whereof I have signed my 15 name to this specification in the presence of two subscribing witnesses.

RONALD F. McFEELY.
